UNITED STATES PATENT OFFICE.

FRANK W. CALVERT, OF NARBERTH, PENNSYLVANIA, ASSIGNOR TO THE CHARLES E. HIRES COMPANY, OF PHILADELPHIA, PENNSYLVANIA, A CORPORATION OF PENNSYLVANIA.

DESIGN FOR A LIQUID-DISPENSING FOUNTAIN.

41,365.

Specification for Design.

Patented May 9, 1911.

Application filed August 19, 1908. Serial No. 449,385. Term of patent 14 years.

To all whom it may concern:

Be it known that I, FRANK W. CALVERT, a citizen of the United States, and a resident of Narberth, Montgomery county, Pennsylvania, have invented a certain new, original, and ornamental Design for a Liquid-Dispensing Fountain, reference being had to the accompanying drawing, forming part thereof, showing a perspective view illustrating my design for a liquid-dispensing fountain.

This design comprises a base structure substantially cylindrical in shape, with a substantially flat top and bottom; the central portion bulging slightly and joining, at top and bottom of said base, annular ribs or projections which increase slightly in diameter from the point where the central body joins the first of said annular ribs; those at the top terminating adjacent a horizontal element forming the actual top of said base. The top is provided with ornamental projections adjacent the margin of the same, with a substantially circular plate in the center having radiating projections, while the

bottom of said base is provided with ornamental feet projecting from the lower outwardly extending rib; a pair of such feet being shown. Surmounting the top of the base portion of the fountain is a curved arm structure extending from an ornamental base element mounted on said top and having at its upper end a rectangular shell from which an ornamental tube depends and from the top of which a bent arm terminating in a ball extends toward the front. Surmounting said rectangular box-like portion is an ornamental shell having a bulging central part upon which is mounted a syrup jar semi-spherical in shape surmounted by an ornamental cap.

I claim:

The ornamental design for a liquid-dispensing fountain as shown and described.

FRANK W. CALVERT.
